CLAIM

The ornamental design for a device for spreading topical skin adhesive as shown and described.

DESCRIPTION

FIG. 1 is a perspective view of a device for spreading topical skin adhesive, showing our new design;

FIG. 2 is a top plan view of the device of FIG. 1, the opposite bottom plan view being a mirror image thereof;

FIG. 3 is a side elevational view of the device of FIG. 1, the opposite side elevational view being a mirror image thereof; FIG. 4 is a first end elevational view of the device of FIG. 1; and,

FIG. 5 is a second end elevational view of the device of FIG. 1.

The evenly-spaced broken lines in the drawings are included for the purpose of illustrating portions of the device for spreading topical skin adhesive that form no part of the claimed design.

1 Claim, 4 Drawing Sheets
